UNITED STATES PATENT OFFICE.

LARS O. GRONDAHL, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed August 31, 1923, Serial No. 660,352. Renewed March 2, 1927.

My invention relates to railway traffic controlling apparatus.

I will describe one form of apparatus embodying my invention, and will then point 5 out the novel features thereof in claims.

In the accompanying drawings, Fig. 1 is a diagrammatic view showing one form of apparatus embodying my invention, and Fig. 10 2 is an end view of one of the translating devices D shown in Fig. 1.

Referring first to Fig. 1, the reference character Q designates the track rails of a railway along which traffic normally moves in the direction indicated by the arrow. 15 These rails are divided by insulated joints 22 into a plurality of blocks A—B, B—C, etc. Located adjacent the entrance end of each block is a signal designated by the reference character S with an exponent corresponding to the location, each of which 20 signals in the form here shown comprises three electric lamps G, Y and R, adapted when lighted to indicate "proceed," "caution" and "stop," respectively. These signals 25 are controlled by the means which I will now describe.

Referring particularly to the apparatus located at point B, this apparatus comprises 30 three devices D, E and F, each of which functions as a relay. Device D comprises two semi-cylindrical plates 4 and 4^a (see also Fig. 2), the outer surfaces of which plates are coated with thermo-sensitive substances 2 and 2^a respectively. Each thermo-sensitive 35 substance is in turn surrounded by a semi-cylindrical electrode 3 or 3^a of metal. Located within the tube formed by these elements is an electron emitting member 19, which, as here shown, is a filament adapted 40 to be heated by the passage of an electric current, and interposed between the filament and the two plates is a grid 11, which, as will be explained hereinafter, serves to control the flow of electrons from the filament 45 19 to the plates 4 and 4^a.

The device E is similar in every respect to the device D. The device F is also similar to device D, except that it contains no grid. The device F is provided, however, with a 50 winding 13 adapted when supplied with electric current to create a magnetic field which prevents the flow of electrons from the filament 21 to the plates 10 and 10^a.

Each device D, E and F will usually be

enclosed in a bulb or tube from which the 55 air is exhausted or which contains a suitable non-oxidizing gas.

Each device D, E and F is so designed that the thermo-sensitive substances are heated by the bombardment of electrons flowing 60 from the filament to the plates, or by ions caused by electron emission, or by both. In any event, the bombardment of the plates is due to the emission of electrons from the filament. These thermo-sensitive substances 65 have negative temperature coefficients, so that the electrical resistance of each substance decreases with an increase of the temperature of the substance. These substances may, for example, be cupric oxide, cuprous 70 oxide, or any other substance having high negative temperature coefficients.

The filaments 19, 20 and 21 of the three devices D, E and F are constantly heated by electric current which is supplied by the 75 secondary 23 of a transformer T^b, these filaments being connected between points 27 and 28 on said secondary. The filament circuits will be obvious from the drawing without further explanation. 80

The primary 24 of the transformer T^b is constantly supplied with alternating current from a transmission line 25, which in turn is supplied with current by a generator 26.

The device D is provided with a plate circuit which passes from point 27 on secondary 23, through wire 51, filament 19, plates 4 and 4^a in multiple, wires 35 and 35^a in multiple, wire 33, and wire 34 to point 32 on secondary 23. The device E is provided 85 with a similar plate circuit which passes from point 27 on secondary 23, through wire 51, filament 20, plates 7 and 7^a in multiple, and wires 36 and 34 to point 32 on secondary 23. The device F is provided with one plate 90 circuit which passes from point 27 on secondary 23, through wire 51, filament 21, plate 10, and wire 37 to point 29 on secondary 23. This device is provided with a second plate circuit which passes from point 27, 100 through wire 51, filament 21, plate 10^a, and wires 38, 36 and 34 to point 32 on the secondary of transformer T^b. It will be observed, therefore, that the plate circuits of all the devices are constantly energized with 105 alternating current.

The winding 13 on device F is connected across the track rails of block A—B, which

rails, as will hereinafter appear, are supplied with alternating current of normal or reverse relative polarity. It follows that as long as section A—B is unoccupied winding 13 is energized, with the result that bombardment against the plates 10 and 10^a is prevented, and the thermo-sensitive substances 8 and 8^a are consequently cool. When block A—B is occupied, however, the winding 13 is de-energized and there is then no opposition to the bombardment against the plates 10 and 10^a, with the result that the thermo-sensitive substances 8 and 8^a are heated.

Connected in multiple with the winding 13 is the primary 15 of a transformer 14. The middle point of secondary 52 of this transformer is connected by a wire 18 with wire 53, and so with the filaments 19 and 20 of the devices D and E. The right-hand terminal of the secondary 52 is connected by a wire 17 with the grid 12 of the device E, while the left-hand terminal of this secondary is connected by a wire 16 with the grid 11 of the device D. It follows that when the block A—B is unoccupied there will be a difference of potential between the filament and grid of each device D and E, but that at any given instant the polarity of the grid in the device D will be opposite to the polarity of the grid in device E.

Each device D and E is so designed and proportioned that if the plates are positive with respect to the filament at the same instant that the grid is positive with respect to the filament, a free flow of electrons will occur from filament to plates, so that the thermo-sensitive substances in these devices will be heated. If, however, the grid is deenergized, or if the plate is positive with respect to the filament at the same instant that the grid is negative with respect to the filament, the flow of electrons from filament to plates will be prevented and so the thermo-sensitive substances will be cool.

45 The control of signal S^B is as follows:

The proceed lamp G is provided with a circuit which passes from point 30 on transformer secondary 23, through wire 39, lamp G, wire 40, thermo-sensitive substance 2^a of device D, and wires 35^a, 33 and 34 to point 32 on transformer secondary 23. The caution lamp Y is provided with a circuit which passes from point 30, through wires 39 and 41, lamp Y, wire 42, thermo-sensitive substance 5^a of device E, and wires 36 and 34 to point 32. The stop lamp R is provided with a circuit which passes from point 30, through wires 39, 41 and 43, lamp R, wire 44, thermo-sensitive substance 8^a of device F and wires 38, 36 and 34 to point 32. Each of these circuits is so designed and proportioned that the lamp is extinguished when the thermo-sensitive substance is cool but is lighted when the thermo-sensitive substance is heated by bombardment.

In addition to the control of the lamps of signal S^B, the three devices D, E and F also control the supply of current to the rails of block B—C. When winding 13 on device F is de-energized so that the thermo-sensitive substances of this device are heated, current passes from point 29 on transformer secondary 23, through wire 37, thermo-sensitive substance 8, wires 47 and 46, the lower track rail Q, then through the apparatus at point C to the upper track rail Q and from that rail through wire 45 to point 31 on transformer secondary 23. This current I will term "current of reverse relative polarity". When winding 13 and transformer primary 15 are energized with current of normal relative polarity, the thermo-sensitive substances in device D are heated, and current then flows from point 32 on transformer secondary 23, through wires 34, 33 and 35, thermo-sensitive substance 2 of device D, wires 50, 48 and 46 to the lower rail Q, thence through the apparatus at point C and the upper rail Q, and from that rail through wire 45 to point 31 on transformer secondary 23. If the current supplied to transformer primary 15 is of reverse relative polarity, the thermo-sensitive substances in device E are heated, whereas the thermo-sensitive substances in device D are cool, so that current then passes from point 32, through wires 34 and 36, thermo-sensitive substance 5 of device E, wires 49, 48 and 46 lower rail Q, the apparatus at point C, upper rail Q and wire 45 to point 31 on secondary 23. When either device D or E is functioning in this manner, current of what I will term "normal relative polarity" is supplied to the rails of block B—C, it being understood that at such times device F is not functioning, and so the supply of current of reverse relative polarity is discontinued.

The grid and plate circuits for devices D and E are so arranged that when current of normal relative polarity is supplied to the rails of block A—B the plates of device D are positive with respect to the filament at the same instant that the grid of this device is positive with respect to the filament so that this device D is active. Proceed lamp G is then lighted and current of normal relative polarity is supplied to the rails of block B—C. At such time the plates of device E are positive with respect to the filament at the same instant that the grid of this device is negative with respect to the filament, so that the device E is not active. The device F is at such times inactive because its winding 13 is energized. When current of reverse relative polarity is supplied to the rails of block A—B the device E is active because the plates of this device are positive with respect to the filament at the same instant that the grid is positive with respect to the filament, so that the caution lamp Y is then lighted.

and current of normal relative polarity is again supplied to the rails of block B—C. Device D is then inactive because its plates are positive with respect to the filament at 5 the same instant that its grid is negative with respect to the filament, so that lamp G is extinguished. When device E is active, device F is, of course, inactive, because its winding 13 is energized, it being understood 10 that the relative polarity of the current supplied to winding 13 is immaterial in so far as concerns the suppressing of the flow of electrons from filament to plates in this device. When block A—B is occupied, devices D and E are both inactive because of 15 the grids of these devices are de-energized, so that lamps G and Y are both extinguished. Device F is then active, however, because its winding 13 is de-energized, so that stop lamp 20 R is lighted and current of reverse relative polarity is supplied to the rails of block B—C.

The apparatus located at each point A and C is exactly the same as the apparatus 25 located at point B and described in detail hereinbefore.

As shown in the drawing, the block immediately to the left of point A is occupied by a train W, so that the device F at point A 30 is active and the devices D and E at this point are inactive. Stop lamp R of signal S^A is accordingly lighted and current of reverse relative polarity is supplied to the rails of block A—B. Device E at point B 35 is accordingly active, whereas the devices D and F are inactive so that the caution lamp Y of signal S^B is lighted and current of normal relative polarity is supplied to the rails of block B—C. Device D at point 40 C is accordingly active, whereas devices E and F at this point are inactive, so that proceed lamp G of signal S^C is lighted and current of normal relative polarity is supplied to the rails of the block to the right 45 of point C.

I do not claim as my invention the broad combination of a thermo-sensitive substance heated by bombardment of electrons from a hot filament and a circuit controlled by 50 the temperature of said substance, such invention being disclosed and claimed in an application for Letters Patent of the United States filed by Frank N. Waterman on the 19th day of October, 1923, Serial No. 55 669,578.

Although I have herein shown and described only one form of apparatus embodying my invention, it is understood that various changes and modifications may be 60 made therein within the scope of the appended claims without departing from the spirit and scope of my invention.

Having thus described my invention, what I claim is:

65 1. Railway traffic controlling apparatus

comprising an electron emitting member, a thermo-sensitive substance heated by bombardment due to emission of electrons from said member, train controlled means for governing the bombardment of said substance, and a traffic governing device controlled by the temperature of said substance. 70

2. Railway traffic controlling apparatus comprising an electron emitting member, a thermo-sensitive substance heated by bombardment due to emission of electrons from said member, train controlled means for governing the bombardment of said substance, a circuit including said substance and a source of current, and a traffic governing device controlled by the flow of current in said circuit. 75

3. Railway traffic controlling apparatus comprising an electron emitting member, a thermo-sensitive substance heated by bombardment due to emission of electrons from said member, train controlled means for governing the bombardment of said substance, and a circuit including said substance and a source of current and a traffic 80 governing device. 85

4. Railway traffic controlling apparatus comprising an electron emitting member, a thermo-sensitive substance heated by bombardment due to emission of electrons from said member, a track circuit including a source of current and the rails of a railway track, means controlled by said track circuit for governing the bombardment of said substance, and a traffic governing device controlled by the temperature of said substance. 95

5. Railway traffic controlling apparatus comprising an electron emitting member, a thermo-sensitive substance heated by bombardment due to emission of electrons from said member, a track circuit including a source of current and the rails of a railway track, means controlled by said track circuit for governing the bombardment of said substance, a circuit including said substance and a source of current, and a traffic governing device controlled by the flow of current in said circuit. 105

6. Railway traffic controlling apparatus comprising an electron emitting member, a thermo-sensitive substance heated by bombardment due to emission of electrons from said member, a winding arranged when energized to create a magnetic field which prevents such bombardment of said substance, a track circuit including a source of current and the rails of a railway track and said winding, and a traffic governing device controlled by the temperature of said substance. 115

7. Railway traffic controlling apparatus comprising an electron emitting member, a thermo-sensitive substance heated by bombardment due to emission of electrons from said member, a winding arranged when en- 120 125 130

4
 ergized to create a magnetic field which prevents such bombardment of said substance, a track circuit including a source of current and the rails of a railway track and said winding, and a signal circuit including said substance and a source of current and a stop lamp.

5. Railway traffic controlling apparatus comprising an electron emitting member, a 10 thermo-sensitive substance heated by bombardment due to emission of electrons from said member, a winding arranged when energized to create a magnetic field which prevents such bombardment of said substance, train controlled means for governing the energization of said winding, and a traffic governing device controlled by the temperature of said substance.

6. Railway traffic controlling apparatus comprising an electron emitting member, a 20 thermo-sensitive substance heated by bombardment due to emission of electrons from said member, a grid for controlling the bombardment of said substance, train controlled means for governing the energization of said grid, and traffic governing means controlled by the temperature of said substance.

7. Railway traffic controlling apparatus comprising an electron emitting member, a 30 plate, a thermo-sensitive substance arranged to be heated by bombardment due to electrons flowing from said member to said plate, a plate circuit including said member and said plate and a source of alternating current, a grid interposed between said member and said plate, a grid circuit including said member and said grid, the parts being so arranged that said thermo-sensitive substance is heated by bombardment when said grid circuit is energized by alternating current in phase with said plate circuit current but not when the grid circuit is energized by alternating current of the opposite phase and when the grid circuit is de-energized, train controlled means for governing the energization of said grid circuit, and traffic governing means controlled by the temperature of said thermo-sensitive substance.

8. Railway traffic controlling apparatus comprising an electron emitting member, a 40 plate, a thermo-sensitive substance arranged to be heated by bombardment due to electrons flowing from said member to said plate, a plate circuit including said member and said plate and a source of alternating current, a grid interposed between said member and said plate, a grid circuit including said member and said grid, the parts being so arranged that said thermo-sensitive substance is heated by bombardment when said grid circuit is energized by alternating current in phase with said plate circuit but not when said grid circuit is energized by al-

ternating current of the opposite phase and when the grid circuit is de-energized, train controlled means for governing the energization of said grid circuit, a circuit including said thermo-sensitive substance and a 70 source of current, and a traffic governing device controlled by the flow of current in said last mentioned circuit.

9. Railway traffic controlling apparatus comprising an electron emitting member, a 75 plate, a thermo-sensitive substance arranged to be heated by bombardment due to electrons flowing from said member to said plate, a plate circuit including said member and said plate and a source of alternating 80 current, a grid interposed between said member and said plate, a grid circuit including said member and said grid, the parts being so arranged that said thermo-sensitive substance is heated by bombardment when 85 said grid circuit is energized by alternating current in phase with said plate circuit current but not when the grid circuit is energized by alternating current of the opposite phase and when the grid circuit is deener- 90 gized, a track circuit including a source of current and the rails of a railway track, means controlled by said track circuit for governing the energization of said grid circuit, and traffic governing means controlled 95 by the temperature of said thermo-sensitive substance.

10. Railway traffic controlling apparatus comprising an electron emitting member, a 100 plate, a thermo-sensitive substance arranged to be heated by bombardment due to electrons flowing from said member to said plate, a plate circuit including said member and said plate and a source of alternating 105 current, a grid interposed between said member and said plate, a grid circuit including said member and said grid, the parts being so arranged that said thermo-sensitive substance is heated by bombardment when said grid circuit is energized by alternating current in phase with said plate circuit current but not when the grid circuit is energized by alternating current of the opposite phase and when the grid circuit is de-energized, a track 110 circuit including track rails and a source of alternating current reversibly connected therewith and the primary of a transformer, the secondary of said transformer being connected with said grid circuit, and traffic 115 governing means controlled by the temperature of said thermo-sensitive substance.

11. Railway traffic controlling apparatus comprising an electron emitting member, a 120 plate, a thermo-sensitive substance arranged to be heated by bombardment due to electrons flowing from said member to said plate, a plate circuit including said member and said plate and a source of alternating 125 current, a grid interposed between said member and said plate, a grid circuit in-

cluding said member and said grid, the parts being so arranged that said thermo-sensitive substance is heated by bombardment when said grid circuit is energized by alternating current in phase with said plate circuit current but not when the grid circuit is energized by alternating current of the opposite phase and when the grid circuit is de-energized, a track circuit including track rails and a source of alternating current reversibly connected therewith and the primary of a transformer, the secondary of said transformer being connected with said grid circuit, a circuit including said thermo-sensitive substance and a source of current, and a traffic governing device controlled by the flow of current in said last mentioned circuit.

15. Railway traffic controlling apparatus comprising an electron emitting member, a plate, a thermo-sensitive substance arranged to be heated by bombardment due to electrons flowing from said member to said plate, a plate circuit including said member and said plate and a source of alternating current, a grid interposed between said member and said plate, a grid circuit including said member and said grid, the parts being so arranged that said thermo-sensitive substance is heated by bombardment when said grid circuit is energized by alternating current in phase with said plate circuit current but not when the grid circuit is energized by alternating current of the opposite phase and when the grid circuit is deenergized, a track circuit including track rails for at times energizing said grid circuit with alternating current in phase with the plate circuit current and at other times energizing the grid circuit with alternating current opposite in phase to the current in the plate circuit, and traffic governing means controlled by the temperature of said thermo-sensitive substance.

45. 16. Railway traffic controlling apparatus comprising two devices, each device including an electron emitting member, a plate, a grid interposed between the member and the plate, and a thermo-sensitive substance arranged to be heated by bombardment due to electrons flowing from the member to the plate; a plate circuit for each device including the plate and member of such device and a source of alternating current, a grid circuit for each device including the member and the grid of such device, train controlled means for supplying alternating current of one relative polarity or the other to said grid circuits, the apparatus being so arranged that when current of one relative polarity is supplied to said grid circuits the plate of the first device is positive with respect to its member at the same instant that the grid of such device is positive with respect to its member while in the second

device the plate is positive with respect to the member at the same instant that the grid is negative with respect to the member, whereas when current of the other relative polarity is supplied to said grid circuits the 70 relative instantaneous polarities in the two devices are reversed, and traffic governing means controlled by the temperature of said thermo-sensitive substances.

17. Railway traffic controlling apparatus 75 comprising two devices, each device including an electron emitting member, a plate, a grid interposed between the member and the plate, and a thermo-sensitive substance arranged to be heated by bombardment due to electrons flowing from the member to the plate; a plate circuit for each device including the plate and member of such device and a source of alternating current, a grid circuit for each device including the member and the grid of such device, train controlled means for supplying alternating current of one relative polarity or the other to said grid circuits, the apparatus being so arranged that when current of one relative 80 polarity is supplied to said grid circuits the plate of the first device is positive with respect to its member at the same instant that the grid of such device is positive with respect to its member while in the second device the plate is positive with respect to the member at the same instant that the grid is negative with respect to the member, whereas when current of the other relative 85 polarity is supplied to said grid circuits the relative instantaneous polarities in the two devices are reversed, a proceed signal controlled by the temperature of the thermo-sensitive substance in one of said devices, and a caution signal controlled by the temperature of the thermo-sensitive substance 90 in the other device.

18. Railway traffic controlling apparatus 95 comprising two devices, each device including an electron emitting member, a plate, a grid interposed between the member and the plate, and a thermo-sensitive substance arranged to be heated by bombardment due to electrons flowing from the member to the plate; a plate circuit for each device including the plate and member of such device and a source of alternating current, a transformer having the middle point of its secondary connected with the members of said two devices and its two terminals connected 100 with the two grids respectively, a track circuit including the track rails of a railway and a source of alternating current reversibly connected therewith and the primary of said transformer, and traffic governing 105 means controlled by the temperature of said thermo-sensitive substances.

19. Railway traffic controlling apparatus 110 comprising three devices each including an electron emitting member, a plate, and a 115

thermo-sensitive substance arranged to be heated by bombardment due to electrons flowing from the member to the plate, the first and second device also including a grid 5 interposed between the member and the plate; a plate circuit for each device including the plate and member of such device and a source of alternating current, a winding for the third device arranged when energized to create a magnetic field which prevents bombardment on the plate of such device, two grid circuits for the first and second devices, respectively; train controlled means for at times supplying alternating 10 current of one relative polarity to said grid circuits and to said winding, and for at other times supplying alternating current of the other relative polarity to said grid circuits and to said winding, and for at still 15 other times discontinuing the supply of current to said grid circuits and said winding; the apparatus being so arranged that when alternating current of one relative polarity is supplied to said grid circuits the plate and 20 grid of the first device are simultaneously of the same polarity and the plate and grid of the second device are simultaneously of opposite polarity, whereas when alternating current of the other relative polarity is supplied to said grid circuits the plate and 25 grid of the first device are simultaneously of opposite polarity and the plate and grid of the other device are simultaneously of the same polarity, and traffic governing means 30 controlled by the temperature of said 35 thermo-sensitive substances.

20. Railway traffic controlling apparatus comprising three devices each including an electron emitting member, a plate, and a 40 thermo-sensitive substance arranged to be heated by bombardment due to electrons flowing from the member to the plate, the first and second device also including a grid interposed between the member and the plate; a plate circuit for each device including the plate and member of such device and a source of alternating current, a winding for the third device arranged when energized to create a magnetic field which prevents bombardment on the plate of such device, two grid circuits for the first and second devices, respectively; train controlled means for at times supplying alternating 45 current of one relative polarity to said grid circuits and to said winding, and for at other times supplying alternating current of the other relative polarity to said grid circuits and to said winding, and for at still other times discontinuing the supply of current 50 to said grid circuits and said winding; the apparatus being so arranged that when alternating current of one relative polarity is supplied to said grid circuits the plate and grid of the first device are simultaneously of the same polarity and the plate and grid of the second device are simultaneously of opposite 55 polarities whereas when the polarity of the track current is reversed the plate and grid of the first device are simultaneously of opposite polarities and the plate and grid of the second device are simultaneously of the same polarity.

60. In combination, a railway track divided into a plurality of successive blocks; three devices for each block each device including an electron emitting member, a plate, and a thermo-sensitive substance arranged to be heated by bombardment due to electrons flowing from the member to the plate, the first and second device for each block also including a grid interposed between the member and the plate, and the third device also including a winding arranged when energized to create a magnetic 65

70 the second device are simultaneously of opposite polarity, whereas when alternating current of the other relative polarity is supplied to said grid circuits the plate and grid of the first device are simultaneously of opposite polarity and the plate and grid of the other device are simultaneously of the same polarity, a light signal comprising proceed, caution and stop lamps, and circuits for said lamps including the thermo-sensitive substances of said first, second and third devices, respectively. 75

21. In combination, a railway track divided into a plurality of successive blocks; three devices for each block each device including an electron emitting member, a plate, and a thermo-sensitive substance arranged to be heated by bombardment due to electrons flowing from the member to the plate, the first and second device for each block also including a grid interposed between the member and the plate, and the third device also including a winding arranged when energized to create a magnetic field which prevents bombardment on the plate of such device; a plate circuit for each device including the plate and member of such device and a source of alternating current, means controlled by the devices for each block and operating to supply alternating current of normal relative polarity to the rails of the block next in the rear when the thermo-sensitive substance of either the first or second device is heated and to supply alternating current of reverse relative polarity to the rails of such block in the rear when the thermo-sensitive substance of the third device is heated, means for each block for supplying alternating current from the track rails to the winding for the third device and also to the grid and member of the first and second devices, the apparatus being so arranged that when the polarity of the track current is normal the plate and grid of the first device are simultaneously of the same polarity and the plate and grid of the second device are simultaneously of opposite polarities whereas when the polarity of the track current is reversed the plate and grid of the first device are simultaneously of opposite polarities and the plate and grid of the second device are simultaneously of the same polarity. 100

22. In combination, a railway track divided into a plurality of successive blocks; three devices for each block each device including an electron emitting member, a plate, and a thermo-sensitive substance arranged to be heated by bombardment due to electrons flowing from the member to the plate, the first and second device for each block also including a grid interposed between the member and the plate, and the third device also including a winding arranged when energized to create a magnetic 105 110 115 120 125 130

field which prevents bombardment on the plate of such device; a plate circuit for each device including the plate and member of such device and a source of alternating current, means controlled by the devices for each block and operating to supply alternating current of normal relative polarity to the rails of the block next in the rear when the thermo-sensitive substance of either the first or second device is heated and to supply alternating current of reverse relative polarity to the rails of such block in the rear when the thermo-sensitive substance of the third device is heated, means for each block for supplying alternating current from the track rails to the winding for the third device and also to the grid and member of the first and second devices, the apparatus being so arranged that when the polarity of the track current is normal the plate and grid of the first device are simultaneously of the same polarity and the plate and grid of the second device are simultaneously of opposite polarities whereas when the polarity of the track current is reversed the plate and grid of the first device are simultaneously of opposite polarities and the plate and grid of the second device are simultaneously of the same polarity, and signals for the blocks controlled by the temperature of the thermo-sensitive substance of said devices.

23. In combination, a railway track divided into blocks, devices for each block including a thermo-sensitive substance and means for heating said substance by bombardment, train controlled means for each block for governing the bombardment in the associated devices, and means controlled by the devices of each block for supplying current to the rails of the block next in the rear.

24. In combination, a railway track divided into blocks, devices for each block including a thermo-sensitive substance and

means for heating said substance by bombardment, train controlled means for each block for governing the bombardment in the associated devices, and means controlled by the devices of each block for supplying current of one polarity or the other to the rails of the block next in the rear.

25. Railway traffic controlling apparatus comprising a thermo-sensitive substance, means for heating said substance by electronic bombardment, and train controlled means for governing such bombardment.

26. Railway traffic controlling apparatus comprising an electron emitting member, a thermo-sensitive substance heated by bombardment due to emission of electrons from said member, and train controlled means for governing such bombardment.

27. The method of controlling railway traffic which consists in heating a thermo-sensitive substance by bombardment due to the emission of electrons, and governing such bombardment by the presence and absence of trains.

28. Railway traffic controlling apparatus comprising an electron emitting member, a thermo-sensitive substance heated by bombardment due to emission of electrons from said member, train controlled means for governing such bombardment, and a traffic controlling device controlled by the temperature of said substance.

29. In combination, a section of railway track, a track circuit including the rails of said section and a source of current, an electron emitting member, a thermo-sensitive substance heated by bombardment due to emission of electrons from said member, a winding associated with said track circuit for governing such bombardment, and traffic governing means controlled by said thermo-sensitive substance.

In testimony whereof I affix my signature.

LARS O. GRONDAHL.
